HEAT SEALER FOR PLASTICS OR THE LIKE

Theodore R. Finke, Euclid, Ohio, assignor to The Euclid Products Co. Inc., Willoughby, Ohio, a corporation of Ohio

Filed July 13, 1962, Ser. No. 70,924

Term of patent 14 years

(Cl. D55—1)

Fig. 1

FIGURE 1 is a side view of a heat sealer for plastics, or the like, showing my new design;

The dominant features of my design reside in the portions shown in full lines.

I claim:

The ornamental design for a heat sealer for plastics or the like, substantially as shown and described.
